SHOE MACHINE

Bernhardt Jorgensen, Marblehead, Mass., assignor to United Shoe Machinery Corporation, Flemington, N. J., a corporation of New Jersey

Application January 25, 1943, Serial No. 473,475

24 Claims. (Cl. 12—14)

This invention relates to machines for use in the manufacture of shoes, and more particularly to machines having means for trimming surplus material from the margin of an upper on a last preparatory to the lasting of the margin of the upper inwardly over an insole on the last. The invention is herein illustrated as applied to a power-operated toe-lasting machine having such trimming means and constructed generally as disclosed in United States Letters Patent No. 2,324,509, granted on July 20, 1943, on an application of mine, but it is to be understood that the invention is not limited to that particular machine or to machines which last the margin of the upper over an insole after it has been trimmed.

The machine shown in the above-mentioned Letters Patent is provided with upper-trimming means movable outwardly from opposite the bottom of the last to trim from the outspread margin of the toe-end portion of a multi-ply upper on the last all but the outer layer of the upper materials, so that the margin of the outer layer will lie next to the insole when it is lasted inwardly over the insole. The upper-trimming means comprises a middle trimmer movable lengthwise of the last and a pair of side trimmers, movable widthwise of the last to act on the upper prior to the action of the middle trimmer thereon, the several trimmers having cutting edges arranged to cut the inner layer or layers of the upper materials on a line generally parallel to the edge of the last bottom. Before the shoe is presented to the machine the margins of all the layers at the sides of the toe are slit in directions transverse to the edge of the last bottom, and accordingly the trimmers in operating as above described sever the surplus marginal material from the rest of the upper materials. Preparatory to the upper-trimming operation the toe-end portion of the upper is wiped heightwise of the last and is thus conformed to the contour of the last by a flexible toe former, adjacent to which are wipers for wiping the margin of the outer layer of the upper inwardly over the insole. Associated respectively with the several trimmers are a plurality of grippers which grip the margin of the multi-ply upper at the end and the sides of the toe respectively and pull it outwardly, the wipers serving as a support for the outspread margin of the upper controlled by the grippers. The several grippers are so controlled as to release the margin of the upper substantially at the time when the side trimmers, operating on the upper as above described prior to the middle

trimmer, begin their trimming action on the upper materials, all the grippers being then moved farther outwardly to avoid interference with the trimmers.

One object of the present invention is to provide upper-trimming means so constructed as to eliminate the need for slitting the margin of the upper at the sides of the toe, as above described, prior to the upper-trimming operation. For the purpose in view, the construction herein shown is such that the ends of the strip of waste material produced by the cut on a line generally parallel to the edge of the last bottom are severed from the rest of the upper materials in the course of the upper-trimming operation. More particularly, as herein illustrated, the side trimmers are provided not only with cutting edges arranged to cut the inner layer or layers of the materials on the above-mentioned line, but also with cutting edges arranged to extend transversely of the edge of the last bottom and to act only on the same inner layer or layers to sever the ends of the strip of waste material. Not only, therefore, is the necessity for a prior upper-slitting operation at the sides of the toe eliminated, but the outer layer of the upper materials is left without any such slits, thus avoiding possibility of damage if the slits should extend too far inwardly from the edge of the upper.

Another object of the invention is to provide for still better cooperation than heretofore between the upper-trimming means and the means for gripping and pulling the margin of the upper materials preparatory to the upper-trimming operation. To insure the most desirable time relation between the operative movements of the trimmers and the release of the upper by the grippers associated therewith, the construction herein shown provides for such release of the upper in response to the movements of the trimmers. To this end, each gripper includes a link through which one of its jaws is held in upper-gripping position, and the link is disconnected from that jaw by the action of the corresponding trimmer thereon just before the trimmer arrives in a position where the gripper would interfere with its further movement. In an organization such as herein shown, comprising a middle trimmer and side trimmers which act on the upper prior to the middle trimmer, a further advantage involved in this construction is that the gripper associated with the middle trimmer retains its hold on the upper after the grippers associated with the side trimmers have released the upper, there being substantially the same co-

ordination between the movement of the middle trimmer and the release of the upper by the gripper associated therewith as between the movements of the side trimmers and the release of the upper by the corresponding grippers. Accordingly, the margin of the upper is maintained under as effective control at the end of the toe as at the sides of the toe for the upper-trimming operation.

The above and other features of the invention, including various novel details of construction and combinations of parts, will now be more particularly described with reference to the accompanying drawings and thereafter pointed out in the claims.

In the drawings,

Fig. 1 is a view partly in left-hand side elevation and partly in section of the upper portion of a machine constructed generally as disclosed in the previously mentioned Letters Patent but modified for purposes of this invention;

Fig. 2 is mainly a plan view on a larger scale of a portion of the structure shown in Fig. 1, with the parts in the positions which they occupy at the beginning of the upper-trimming operation;

Fig. 3 is a view in elevation from the right-hand side of the machine of the right-hand side trimmer, with portions of the structure broken away;

Fig. 4 shows a portion of the structure shown in Fig. 3, as viewed from the left-hand side of Fig. 3;

Fig. 5 is mainly a sectional view illustrating the relation to the shoe of the left-hand side trimmer and of parts associated therewith at the same time in the operation of the machine as in Fig. 2;

Fig. 6 is a sectional view illustrating the relation to the shoe of the middle trimmer and of parts associated therewith as it performs its upper-trimming operation after the operation of the side trimmers; and

Fig. 7 is a view similar to Fig. 6, showing the parts as they appear immediately after the completion of the upper-trimming operation.

In view of the disclosure in the above-mentioned Letters Patent, only as much of the machine as it is necessary to refer to for an understanding of the present invention will be herein described. The machine is provided as heretofore with a member 2 arranged to engage the bottom of the toe end of the insole to determine the position of the shoe heightwise in the machine when the operator presents it bottom upward for the operation of the machine thereon, and associated with this member are a plurality of pins 4 arranged to extend through holes in the insole into holes in the bottom of the last further to determine the position of the shoe. Early in the power operation of the machine the shoe is clamped against the member 2 by an upwardly movable toe rest 6. The shoe is presented with the outturned margin of the toe end of the multiply upper between the open jaws of a plurality of grippers, comprising an end gripper 8 which grips the upper at the end of the toe and side grippers 10 which grip it at the sides of the toe. These grippers are closed on the upper and are operated to pull it respectively lengthwise and widthwise of the shoe as more particularly herein-after described. While the grippers are thus pulling the upper its toe-end portion is wiped heightwise of the last and is conformed to the contour of the last by upward movement of a substantially U-shaped flexible toe former 12 carried by a support 14 to which upward movement is imparted by a pair of fluid-operated pistons 16,

one of which is shown in Fig. 1. Features of the mechanism shown for operating the support 14 and for controlling the toe former are claimed in Letters Patent No. 2,354,685, granted on August 1,

5 1944, on an application of mine. Also carried by the support 14 are wipers 18 located in a plane immediately above the toe former and arranged to support the margin of the upper in outspread relation to the edge of the last bottom for the 10 upper-trimming operation after the wipers and the toe former have received their upward movement. For thus trimming the margin of the upper there are provided a middle trimmer 20 movable outwardly lengthwise of the shoe and side trimmers 22 movable outwardly widthwise of the 15 shoe from positions opposite the bottom of the shoe to sever from the upper materials the margin of all but the outer layer of the materials, leaving the margin of the outer layer to be thereafter wiped inwardly over the insole by the wipers 18 into position to be secured to the insole by cement applied to the shoe by means not herein shown. In time relation to the outward movements of the trimmers the grippers are caused to release the upper and are moved farther outwardly to avoid interference with the trimmers.

The several trimmers are supported on a carrier 24 by downward movement of which they are carried into positions to operate on the shoe and by upward movement of which they are thereafter carried away from the shoe. The middle trimmer 20 comprises a knife 26 having a cutting edge 27 (Fig. 2) curved in general similarity to the curvature of the edge of the insole around the end of the toe, and the side trimmers 22 comprise knives 28 having cutting edges 29 (Figs. 3 and 4) which in the construction shown are straight lengthwise of the shoe. The several knives, in operating on the upper, move in a plane parallel to the top faces of the wipers 18 with their cutting edges spaced from these faces a distance substantially equal to the thickness of the outer layer of the upper materials, so that they cut through the inner layer or layers of the upper materials on a line generally parallel to the edge of the last bottom while leaving the margin of the outer layer intact to be lasted inwardly over the insole. It will be understood that the toe end of the upper materials will usually comprise at least three layers, including a lining and a toe box in addition to the outer layer.

Each side knife 28 is secured to a knife holder 30, and as fully disclosed in Letters Patent No. 2,324,509, the two holders 30 are moved on the carrier 24 along guideways curved about a vertical axis located opposite the end of the toe of the shoe to impart operative trimming movements to the side knives. As also fully disclosed therein, such movements are imparted to the knife holders 30 by a slide 32 (Fig. 1) movable in directions lengthwise of the shoe along guideways on the carrier 24. The slide is moved in a rearward direction, i. e., toward the left in Fig. 1, thus to operate the side knives by a fluid-operated piston 34 movable upwardly in a cylinder 36 and connected by a link 38 to one arm of a three-armed lever 40 mounted on a pin 42 on the carrier 24, another arm of this lever being connected by a link 44 to a pin 46 on the slide 32. Pivotally mounted on this pin to swing in directions heightwise of the shoe is an arm 48 which carries the middle knife 26. The arm is held initially upright by a spring 50 connected to it and to the slide 32, the limit of its upward swinging movement being determined by engagement of a

lug 52 on its rear end with the top of the slide. It will be evident that the arm 48 is carried rearwardly by the slide 32, but it remains upraised until the side knives 28 have been swung substantial distances away from each other in their operative trimming movements. The arm is then swung downwardly to carry the cutting edge of the knife 26 to the same plane as the cutting edges of the side knives, and by further movement of the slide 32 thereafter the knife 26 is moved rectilinearly to complete the upper-trimming operation begun by the side knives in their earlier action on the upper at the sides of the toe. The arm 48 is swung downwardly as above described by a lever 54 pivotally mounted on a pin 56 on the carrier 24 and having thereon a roll 58 arranged to engage an inclined face 60 on the arm. Operative movement is imparted to the lever 54 by a roll 62 carried by one arm of the three-armed lever 40, and arranged to engage a cam face 64 on the lever 54, all as more fully disclosed in Letters Patent No. 2,324,509.

For the accomplishment of one of the objects of this invention, there is associated with each of the side-trimming knives 28 a substantially vertical knife 66 (Figs. 3 and 4) having a cutting edge 68 inclined heightwise and widthwise of the shoe. The knife 66 is secured to a plate 70 pivotally mounted on a pin 72 which is supported by the upper end of a plate 74 fast on that side of the knife holder 30 which faces toward the heel end of the shoe. A screw 76 threaded in the holder 30 and extending through a slot 78 in the plate 74 holds the plate in fixed relation to the holder while permitting it to be adjusted in directions heightwise of the shoe to position the knife 66 in exactly the right relation to the knife 28. A leaf spring 80 secured to the plate 70 and bearing at its upper end on the holder 30 holds the knife 66 against the side of the knife 28 and is yieldable to permit release of any shred of upper material that may become wedged between the two knives. The relation of the two knives 66 to the side-trimming knives 28 is such that as the latter move outwardly to perform the upper-trimming operation the knives 66 sever from the rest of the upper materials the opposite ends of the strip of waste material produced by the action of the side knives 28 and the middle knife 26 in cutting the inner layer or layers of the upper materials on a line parallel to the edge of the last bottom. The knives 66 act only on the layer or layers which are acted upon by the knives 26 and 28, and accordingly leave the outer layer of the upper materials without any slits therein at the sides of the toe. Not only, therefore, is the necessity avoided of slitting the several layers at the sides of the toe before presenting the shoe to the machine, as has been the practice heretofore in the use of a machine such as shown in Letters Patent No. 2,324,509, but danger also is avoided of possible damage to the shoe in case such slits in the outer layer should extend too far inwardly from the edge of the upper.

The grippers 8 and 10 and their operating mechanisms are constructed for the most part substantially as disclosed in Letters Patent No. 2,324,509 and will be herein briefly described. The grippers are mounted on a substantially horizontal gripper support 82 which is pivotally mounted at its rear end on the frame for adjusting movements in directions heightwise of the shoe. The end gripper 8 comprises a pair of jaws 84 and 86 (Figs. 6 and 7) arranged to present a substantially horizontal opening between them

to receive the margin of the upper. The lower jaw 84 is fast on a slide 88 movable in directions lengthwise of the shoe along guideways on the support 82, and the upper jaw 86 is mounted on a pin 90 on the lower jaw for swinging movements toward and from the latter. An upwardly extending arm 92 on the jaw 86 is connected by means hereinafter described to a piston 94 movable in a cylinder 96 fast on the slide 88. The jaw 86 is held initially in open position by springs 98 connected thereto as hereinafter described, the piston 94 being then near the inner end of the cylinder 96. The piston is operated to cause the jaws to grip the upper by fluid admitted to the cylinder 96 from a pipe 100 connected to a flexible supply tube (not shown).

Each of the side grippers 10 is generally similar in construction to the end gripper 8 and comprises a lower jaw 102 (Fig. 5) and an upper jaw 104 pivotally mounted at 106 on the lower jaw. The lower jaw of each side gripper is secured to a slide 108 movable in directions widthwise of the shoe along guideways on the support 82. An upwardly extending arm 110 of the upper jaw of each side gripper is connected by means hereinafter described to a piston 112 operating in a cylinder 114 fast on the slide 108, the upper jaw being held normally in open position by springs 116 (Fig. 2) connected thereto as hereinafter described. The closing of each side gripper on the upper results from the admission of fluid to the cylinder 114 through a flexible tube 120 leading from the source of fluid supply. As disclosed in Letters Patent No. 2,324,509, by control of a valve (not herein shown) fluid is admitted to all three cylinders to close all the grippers simultaneously on the upper prior to the starting of the automatic cycle of operations of the machine.

The pulling of the upper by the several grippers is effected by movements of the slides 88 and 108 outwardly along their guideways on the support 82 in directions substantially parallel to the bottom of the toe end of the last. For imparting such upper-pulling movement to the end gripper 8 a lever 122 is pivotally mounted at 124 on the support 82 and is yieldingly connected through a compression spring 126 (Figs. 1 and 2) to a link 128 pivotally connected at one end to the slide 88. As the slide 88 is thus moved in the direction to cause the gripper to pull the upper, the pipe 100 moves with it against the resistance of a spring 130 which later acts to return the slide and the gripper to starting position. The operative movement of the lever 122 is effected by bodily movement of a cylinder 132 which is pivotally connected to the lever and into which operating fluid is delivered through a flexible tube 134 leading from the source of supply. Operative movement of the lever 122 is limited by a stop 136 on the support 82.

The fluid admitted to the cylinder 132 serves also to impart upper-pulling movement to the left-hand side gripper 10. For this purpose there is movably mounted in the cylinder a piston 138 pivotally connected to one arm of a lever 140 mounted to swing about a stud 142 on the support 82. Also mounted to swing about this stud is a forwardly extending lever 144 connected at its front end to the slide 108 carrying the left-hand side gripper. A spring 146 connected to the front end portion of the lever 144 and to the left-hand arm of the lever 140 serves to hold the latter initially in engagement with a stop lug 148 on the lever 144, at which time the piston 138 is near the inner end of the cylinder 132.

Outward movement of the piston when fluid is admitted to the cylinder serves to swing the lever 140 and the lever 144 as a unit about the stud 142 to impart upper-pulling movement to the left-hand side gripper, the spring 146 yielding more or less in response to resistance of the upper to the force of the pull applied thereto and the lever 140 accordingly moving more or less away from the stop lug 148, as illustrated in Fig. 2. Movement of the piston 138 is limited by a stop lug 150 on the support 82. Eventually the left-hand side gripper is returned to its starting position by a spring 152 connected to the right-hand arm of the lever 140.

The mechanism for imparting upper-pulling movement to the right-hand side gripper 10 is of substantially the same construction as that above described as associated with the left-hand side gripper, and corresponding parts are identified by the same reference characters. The lever 140 through which the right-hand gripper is operated is pivotally connected to a piston 154 movably mounted in a cylinder 156 which is pivoted on a stud 158 on the support 82, movement of the piston being limited by a stop lug 160. Fluid is admitted to this cylinder through a pipe 162. As disclosed in Letters Patent No. 2,324,509, fluid is admitted simultaneously to both the cylinders 132 and 156 through an automatically controlled valve (not herein shown) to cause the several grippers to pull the upper.

As hereinbefore explained, release of the margin of the upper by all the grippers has taken place heretofore substantially at the time when the side-trimming knives 28 begin their trimming action on the upper, such release of the upper resulting from release of the operating fluid from the cylinders 96 and 114 by movement of the controlling valve to exhaust position. To afford still better insurance of the proper coordination between the release of the upper by the side grippers and the movements of the trimmers associated therewith, and to permit the end gripper still to control the upper after it has been released by the side grippers and until the middle trimming knife begins its trimming action on the upper, the construction herein shown is such that the release of the upper by each of the several grippers is effected in response to the operative movement of the trimmer associated therewith. For the purpose in view, the piston 94 of the end gripper has pivotally connected thereto a forwardly extending link 164 provided in its front end portion with a slot 166 (Fig. 6) in which a pin 167 carried by the upwardly extending arm 92 of the gripper jaw 86 normally lies, as shown in Fig. 1. The previously mentioned jaw-opening springs 98, which are connected to a pin 168 in the link 164, tend to swing the link upwardly and accordingly hold it normally in a position in which the pin 167 is at the lower end of the slot 166. An upwardly extending portion of the front end of the link is provided with an inclined face 170 arranged to be engaged by a roll 172 mounted on a bracket 174 which is supported on the arm 48 carrying the middle trimming knife 26. In response, therefore, to the operative movement of the middle trimmer lengthwise of the shoe the link 164 is swung downwardly against the resistance of the springs 98 by the action of the roll 172 thereon. In Fig. 6 the parts are shown in the positions which they occupy substantially at the time when the middle trimming knife begins its trimming action on the upper, the link 164 having been swung nearly far

enough to release the pin 167 from the slot 166. Immediately thereafter such release of the pin takes place, thus releasing the pressure of the jaw 86 on the upper and permitting the end gripper 10 to be moved farther outwardly by the action of the spring 126 thereon to avoid interference with the trimmer as the latter moves farther outwardly over the wipers in the manner illustrated in Fig. 7. At this time the pressure of the operating fluid is still maintained in the cylinder 96, outward movement of the piston 94 in the cylinder being limited by its engagement with a pin 176 in the cylinder. The bracket 174, which is U-shaped to provide portions at both sides of the arm 48, is mounted on a pin 178 on the arm and is further held in fixed relation thereto by a bolt 180.

Similarly the piston 112 of each of the side grippers has pivotally connected thereto a link 182 provided with a slot 184 arranged to receive a pin 185 carried by the upwardly extending arm 110 of the jaw 104, the link being urged upwardly by the previously mentioned jaw-opening springs 116 connected to a pin 186 in the link and being provided with an inclined face 188 arranged to be engaged by a roll 190 on the corresponding side knife holder 30. The roll is mounted on a pin 192 adjustable along an inclined slot 194 in the holder 30 to permit the roll to be adjusted in exactly the right relation to the link 182. The pin is held in adjusted position by a nut 196 (Fig. 3) threaded thereon and cooperating with a flange 198 formed on the pin to clamp the pin on the knife holder. It will thus be seen that the two side grippers 10 are caused to release the upper in response to the movements of the side trimmers substantially at the time when the latter begin their trimming action on the upper, by reason of downward swinging movements of the links 182 far enough to release the pins 185 from the slots 184, whereupon the side grippers are moved farther outwardly by the springs 146 to prevent interference between them and the side trimmers. Outward movements of the pistons 112 in the cylinders 114 when the grippers thus release the upper are limited by pins 200 in the cylinders.

The manner of operation of the machine, in so far as it is of interest with reference to the present invention, will now be briefly summarized. Ordinarily the shoe will have been side lasted before it comes to the machine, and before presenting it in position to be operated upon the operator spreads the margin of the toe-end portion of the multi-ply upper outwardly from the edge of the last bottom so that it will readily enter the open jaws of the end and side grippers 8 and 10. He then presents it bottom upward with the toe end of the insole against the member 2 and with the pins 4 extending into the holes provided for them in the bottom of the last, and thereafter causes the several grippers to close on the margin of the upper by admitting operating fluid to the cylinders 96 and 114. If the upper is properly gripped, the operator then starts the cycle of power operations of the machine. Substantially at the beginning of the cycle the toe rest 6 is moved upwardly to clamp the shoe against the member 2, and early in the cycle also fluid is admitted to the cylinders 132 and 156 to cause the end gripper and the side grippers to pull the upper respectively in directions lengthwise and widthwise of the shoe. The support 14 is then moved upwardly to cause the toe former 12 to wipe the toe-end portion of the

upper heightwise of the last and to raise the wipers 18 to positions slightly higher than the edge of the insole, where they serve as supports for the outspread margin of the upper held by the grippers. In proper time relation to the upward movement of the toe former and the wipers the carrier 24 is moved downwardly to carry the upper-trimming means into proper relation to the shoe, and the trimming means is then operated to trim from the outspread margin of the toe end of the upper all but the outer layer of the upper materials. In the upper-trimming operation the two side trimmers 22 are swung outwardly and act on the upper prior to the middle trimmer 20, Figs. 2 and 5 showing the parts as they appear as the side-trimming knives 28 are beginning to trim the upper on a line generally parallel to the edge of the last bottom. At this time the rolls 190 carried by the side trimmers have engaged the inner end portions of the links 182 and have swung the links downward nearly far enough to release the pins 185 from the slots in the links. Immediately thereafter, as the side trimmers continue their outward movements, the pins are released from the slots, thus causing the side gripper jaws to release the upper, whereupon the side grippers are moved farther outwardly away from the shoe by the action of the tensioned springs 146 to prevent interference of these grippers with the side trimmers during further outward movements of the latter. The pressure of the operating fluid, however, is still maintained in the cylinders 114, outward movements of the pistons 112 in the cylinders being limited by the pins 200. In the course of the outward movements of the side trimmers the knives 66 slit the margin of all but the outer layer of the upper materials transversely of the edge of the shoe bottom and thereby sever from the rest of the upper materials the strip of waste material produced by the action of the side trimmers and the middle trimmer.

Immediately after the action of the side trimmers on the upper, the middle trimmer 20, which has been swung downwardly to carry its knife 26 to the same plane as the side knives 28, acts on the portion of the upper around the end of the toe in the same manner as the side knives 28, thus completing the upper-trimming operation. As the middle trimmer is thus operated, its roll 172 serves to impart downward swinging movement to the link 164 and thereby to release the pin 167 from the slot 166 in the link to cause the end gripper 8 to release the upper. Such release of the upper takes place near the beginning of the upper-trimming operation of the middle knife, just after the parts are positioned as illustrated in Fig. 6. Thereupon the end gripper is moved farther outwardly by the spring 126 to avoid interference with the middle trimmer, outward movement of the piston 94 in the cylinder 96 being limited by the pin 176. The positions of the parts substantially at the end of the operative movement of the middle trimmer are illustrated in Fig. 7. Further operations of the machine on the shoe thereafter take place in the manner disclosed in Letters Patent No. 2,324,509. It will be understood that in the course of the further operation of the machine fluid is released from the cylinders 96 and 114, whereupon the pistons 94 and 112 are moved inwardly in the cylinders by the springs 98 and 116, respectively. As the pistons are thus returned the pins 167 and 185 again enter the slots 166 and 184 in

the links 164 and 182 which are swung upwardly by the action of the springs thereon.

Having described the invention, what I claim as new and desire to secure by Letters Patent of the United States is:

1. In a shoe machine, upper-trimming means movable along a plane generally parallel to the bottom of the toe end of a last to trim from the toe end of a multi-ply upper on the last the margin of one or more inner layers of the upper materials while leaving a margin of the outer layer to be lasted inwardly over an insole on the last, a portion of said trimming means being arranged to cut the materials on a line generally parallel to the edge of the last bottom and another portion thereof having cutting edges arranged to extend transversely of the edge of the last bottom and to act only on said inner layer or layers to sever from the body of the materials the ends of the strip produced by said first-named portion.
2. In a shoe machine, upper-trimming means movable outwardly from opposite the bottom of a last to trim from the toe end of a multi-ply upper on the last the margin of one or more inner layers of the upper materials while leaving a margin of the outer layer to be lasted inwardly over an insole on the last, said upper-trimming means having cutting edges arranged to extend respectively in generally parallel relation to the bottom of the toe end of the last and heightwise of the last and to act only on said inner layer or layers to sever completely therefrom a strip extending around the toe end of the last.
3. In a shoe machine, upper-trimming means movable to trim from the toe end of a multi-ply upper on a last the margin of one or more inner layers of the upper materials while leaving a margin of the outer layer to be lasted inwardly over an insole on the last, said upper-trimming means comprising a plurality of trimmers movable respectively in different directions outwardly from positions opposite the bottom of the last to perform the trimming operation, all said trimmers having cutting edges arranged to cut the materials on a line generally parallel to the edge of the last bottom and two of them having also cutting edges arranged to sever from the body of the materials the ends of the strip produced by said first-named cutting edges.
4. In a shoe machine, upper-trimming means movable to trim from the toe end of a multi-ply upper on a last the margin of one or more inner layers of the upper materials while leaving a margin of the outer layer to be lasted inwardly over an insole on the last, said upper-trimming means comprising a middle trimmer movable lengthwise of the last and side trimmers movable widthwise of the last, all said trimmers having cutting edges arranged to cut the materials on a line generally parallel to the edge of the last bottom and the side trimmers having also cutting edges arranged to extend transversely of the edge of the last bottom to sever from the body of the materials the ends of the strip produced by said first-named cutting edges.
5. In a shoe machine, means for positioning the margin of the toe-end portion of a multi-ply upper on a last in outspread relation to the edge of the last bottom, and upper-trimming means movable outwardly from opposite the bottom of the last to trim from said outspread margin by a cut generally parallel to the edge of the last bottom one or more inner layers of the upper materials while leaving a margin of the outer layer to be lasted inwardly over an insole on

the last, said trimming means having cutting edges arranged to extend transversely of the edge of the last bottom and to act only on said inner layer or layers to sever from the body of the materials the ends of the strip resulting from said parallel cut.

6. In a shoe machine, means for positioning the margin of the toe-end portion of a multi-ply upper on a last in outspread relation to the edge of the last bottom, and upper-trimming means comprising a middle trimmer movable outwardly lengthwise of the last and side trimmers movable outwardly widthwise of the last to trim from said outspread margin by a cut generally parallel to the edge of the last bottom one or more inner layers of the upper materials while leaving a margin of the outer layer to be lasted inwardly over an insole on the last, the side trimmers being provided with cutting edges arranged to extend heightwise of the last to sever from the body of the materials the ends of the strip resulting from said parallel cut.

7. In a shoe machine, means for positioning the margin of the toe-end portion of a multi-ply upper on a last in outspread relation to the edge of the last bottom, and means for trimming surplus material from said outspread margin of the upper, said trimming means including knives movable outwardly widthwise of the last from positions opposite the bottom of the last to trim said margin on a line generally parallel to the edge of the last bottom and additional knives movable with said first-named knives to slit the margin of the upper transversely of the edge of the last bottom.

8. In a shoe machine, means for positioning the margin of the toe-end portion of a multi-ply upper on a last in outspread relation to the edge of the last bottom, and means for trimming surplus material from said outspread margin of the upper, said trimming means including knives movable outwardly widthwise of the last from positions opposite the bottom of the last to trim said margin on a line generally parallel to the edge of the last bottom and additional knives movable with said first-named knives to slit the margin of the upper transversely of the edge of the last bottom, and means for yieldingly holding said additional knives against the portions of said first-named knives which are farthest from the extreme toe end of the last.

9. In a shoe machine, upper-trimming means movable to trim surplus material from the margin of a multi-ply upper on a last prior to the lasting of the margin of the upper inwardly over an insole on the last, and upper-gripping means for gripping the margin of the upper and for applying a pull to the upper prior to the upper-trimming operation, said upper-gripping means comprising parts relatively movable to release the upper in response to the operative movement of the upper-trimming means.

10. In a shoe machine, a trimmer movable to trim surplus material from the margin of a multi-ply upper on a last prior to the lasting of the margin of the upper inwardly over an insole on the last, and a gripper for gripping the margin of the upper and for applying a pull to the upper prior to the upper-trimming operation, said gripper comprising a pair of upper-gripping jaws and a jaw-controlling member movable by said trimmer to cause the jaws to release the upper in time relation to the operative movement of the trimmer.

11. In a shoe machine, a trimmer movable to

trim surplus material from the margin of a multi-ply upper on a last prior to the lasting of the margin of the upper inwardly over an insole on the last, a pair of upper-gripping jaws for gripping the margin of the upper and for applying a pull to the upper prior to the upper-trimming operation, and a member connected to one of said jaws for holding it closed on the upper, said member being movable by the trimmer to disconnect it from that jaw and thereby to cause the jaws to release the upper in time relation to the operative movement of the trimmer.

12. In a shoe machine, a trimmer movable to trim surplus material from the margin of a multi-ply upper on a last prior to the lasting of the margin of the upper inwardly over an insole on the last, a pair of upper-gripping jaws for gripping the margin of the upper and for applying a pull to the upper prior to the upper-trimming operation, a jaw-closing member for holding one of said jaws in gripping relation to the upper, and a connection between that jaw and said jaw-closing member, said trimmer having thereon means arranged to act on said connection to cause the jaws to release the upper in time relation to the operative movement of the trimmer.

13. In a shoe machine, a trimmer movable to trim surplus material from the margin of a multi-ply upper on a last prior to the lasting of the margin of the upper inwardly over an insole on the last, a pair of upper-gripping jaws for gripping the margin of the upper and for applying a pull to the upper prior to the upper-trimming operation, a fluid-operated member associated with one of said jaws for holding it in gripping relation to the upper, and a link connecting that jaw to said member, said trimmer having thereon means for moving said link to disconnect that jaw from said member and thereby to cause the jaws to release the upper in time relation to the operative movement of the trimmer.

14. In a shoe machine, means for supporting the margin of a multi-ply upper on a last in outspread relation to the edge of the last bottom, upper-trimming means movable outwardly from opposite the bottom of the last to trim from said outspread margin one or more inner layers of the upper materials while leaving a margin of the outer layer to be lasted inwardly over an insole on the last, and upper-gripping means for gripping the margin of the upper and for pulling it outwardly over said supporting means preparatory to the upper-trimming operation, said upper-gripping means comprising parts relatively movable to release the upper in response to the operative movement of the upper-trimming means.

15. In a shoe machine, upper-trimming means movable outwardly from opposite the bottom of a last to trim surplus material from the margin of the toe-end portion of a multi-ply upper on the last prior to the lasting of the margin of the upper inwardly over an insole on the last, and upper-gripping means for gripping the margin of the toe end of the upper and for applying a pull to the upper prior to the upper-trimming operation, said upper-gripping means comprising parts relatively movable to release the upper in response to the outward movement of the upper-trimming means.

16. In a shoe machine, upper-trimming means movable to trim surplus material from the margin of the toe-end portion of a multi-ply upper

on a last prior to the lasting of the margin of the upper inwardly over an insole on the last, upper-gripping means for gripping the margin of the toe end of the upper and for applying a pull to the upper prior to the upper-trimming operation, said upper-gripping means comprising a plurality of pairs of upper-gripping jaws and jaw-controlling members movable to cause the jaws to release the upper, and means carried by the upper-trimming means for thus moving said jaw-controlling members.

17. In a shoe machine, upper-trimming means movable to trim surplus material from the margin of the toe-end portion of a multi-ply upper on a last prior to the lasting of the margin of the upper inwardly over an insole on the last, said upper-trimming means comprising a plurality of trimmers movable thus to act on the upper respectively at different times, a plurality of grippers associated respectively with said different trimmers for gripping the margin of the toe end of the upper and for applying a pull to the upper prior to the upper-trimming operation, and means to cause said grippers to release the upper in a sequence corresponding to the sequence in which said trimmers act on the upper.

18. In a shoe machine, upper-trimming means movable to trim surplus material from the margin of the toe-end portion of a multi-ply upper on a last prior to the lasting of the margin of the upper inwardly over an insole on the last, said upper-trimming means comprising a middle trimmer movable lengthwise of the last and side trimmers movable widthwise of the last to act on the upper prior to the action of the middle trimmer thereon, a plurality of grippers associated respectively with said different trimmers for gripping the margin of the toe end of the upper and for applying a pull to the upper prior to the upper-trimming operation, and means to cause the grippers associated with the side trimmers to release the upper prior to the gripper associated with the middle trimmer.

19. In a shoe machine, upper-trimming means movable to trim surplus material from the margin of the toe-end portion of a multi-ply upper on a last prior to the lasting of the margin of the upper inwardly over an insole on the last, said upper-trimming means comprising a plurality of trimmers movable respectively in different directions outwardly from positions opposite the bottom of the last to perform the trimming operation, and a plurality of grippers associated respectively with said different trimmers for gripping the margin of the toe end of the upper and for applying a pull to the upper prior to the upper-trimming operation, each of said grippers comprising parts relatively movable to release the upper in response to the operative movement of the trimmer associated therewith.

20. In a shoe machine, upper-trimming means movable outwardly from opposite the bottom of a last to trim surplus material from the margin of the toe-end portion of a multi-ply upper on the last prior to the lasting of the margin of the upper inwardly over an insole on the last, said upper-trimming means comprising a middle trimmer movable lengthwise of the last and side trimmers movable widthwise of the last to act on the upper prior to the action of the middle trimmer thereon, and a plurality of grippers associated respectively with said different trimmers for gripping the margin of the toe end of the upper and for applying a pull to the upper prior to the upper-trimming operation, said grippers

comprising parts relatively movable to release the upper in response to the operative movements of the trimmers associated therewith and in a sequence corresponding to the sequence in which said trimmers act on the upper.

5 21. In a shoe machine, means for supporting the margin of the toe-end portion of a multi-ply upper on a last in outspread relation to the edge of the last bottom, upper-trimming means movable to trim from said outspread margin one or more inner layers of the upper materials while leaving a margin of the outer layer to be lasted inwardly over an insole on the last, said upper-trimming means comprising a plurality of trimmers movable respectively in different directions outwardly from positions opposite the bottom of the last to perform the trimming operation, and a plurality of grippers associated respectively with said different trimmers for gripping the

10 20 margin of the toe end of the upper and for pulling it outwardly over said supporting means preparatory to the upper-trimming operation, said grippers comprising parts relatively movable to release the upper in response to the operative movements of the trimmers associated therewith.

15 22. In a shoe machine, means for supporting the margin of the toe-end portion of a multi-ply upper on a last in outspread relation to the edge of the last bottom, upper-trimming means movable outwardly from opposite the bottom of the last to trim from said outspread margin one or more inner layers of the upper materials while leaving a margin of the outer layer to be lasted inwardly over an insole on the last, said upper-trimming means comprising a middle trimmer movable lengthwise of the last and side trimmers movable widthwise of the last to act on the upper prior to the action of the middle trimmer thereon, and a plurality of grippers associated respectively with said different trimmers for gripping the margin of the toe end of the upper and for pulling it outwardly over said supporting means preparatory to the upper-trimming operation, each of said grippers comprising a pair of upper-gripping jaws and a jaw-controlling member movable to cause the jaws to release the upper in response to the operative movement of the trimmer associated therewith.

20 23. In a shoe machine, means for supporting the margin of the toe-end portion of a multi-ply upper on a last in outspread relation to the edge of the last bottom, upper-trimming means movable to trim from said outspread margin one or more inner layers of the upper materials while leaving a margin of the outer layer to be lasted inwardly over an insole on the last, said upper-trimming means comprising a plurality of trimmers movable respectively in different directions outwardly from positions opposite the bottom of the last to perform the trimming operation, a plurality of grippers associated respectively with said different trimmers for gripping the margin of the toe end of the upper and for pulling it outwardly over said supporting means preparatory to the upper-trimming operation, each of said grippers comprising a pair of upper-gripping jaws and a jaw-controlling member movable to cause the jaws to release the upper in response to the operative movement of the trimmer associated therewith, and means for moving said grippers farther outwardly upon such release of the upper to avoid interference with the trimmers.

25 24. In a shoe machine, means for supporting

the margin of the toe-end portion of a multi-ply upper on a last in outspread relation to the edge of the last bottom, upper-trimming means movable to trim from said outspread margin one or more inner layers of the upper materials while leaving a margin of the outer layer to be lasted inwardly over an insole on the last, said upper-trimming means comprising a plurality of trimmers movable respectively in different directions outwardly from positions opposite the bottom of the last to perform the trimming operation, a plurality of pairs of upper-gripping jaws associated respectively with said different trimmers

for gripping the margin of the toe end of the upper and for pulling it outwardly over said supporting means preparatory to the upper-trimming operation, fluid-operated members associated respectively with said different pairs of jaws for holding one jaw of each pair in gripping relation to the upper, and links connecting said members to the jaws controlled thereby, said links being movable to cause the pairs of jaws to release the upper in response to the operative movements of the trimmers associated therewith.

BERNHARDT JORGENSEN.
